Primary Examiner — Khoa D Huynh*(74) Attorney, Agent, or Firm* — Law Office of Sam Sokhansanj PLLC(57) **ABSTRACT**

A perspiration diverting headband is provided which includes a flexible tubing having a first end and a second end, and an elastic band a first end and a second end, wherein the elastic band extends through and out the first end and second end of the flexible tubing. The headband can further include a first tubular connector secured to the first end of the tubing and at least partially disposed over the elastic band, wherein the elastic band further extends through and out the first tubular connector. The headband may also include a second tubular connector secured to the second end of the tubing and at least partially disposed over the elastic band, wherein the elastic band further extends through and out the second tubular connector. In addition, the headband may include a first slidable fastener and a second slidable fastener for securing the headband to a user's head.

PERSPIRATION DIVERTING HEADBAND

CROSS-REFERENCE TO RELATED
APPLICATIONS

This application is a continuation-in-part of U.S. Non-Provisional application Ser. No. 16/729,431 filed on Dec. 29, 2019, which is incorporated herein by reference in its entirety, which is a division of U.S. Non-Provisional application Ser. No. 14/689,278 filed on Apr. 17, 2015, which is incorporated herein by reference in its entirety, which claims the benefit of U.S. Provisional Application No. 61/980,633 filed on Apr. 17, 2014, which is incorporated herein by reference in its entirety.

BACKGROUND

This section is intended to introduce the reader to aspects of art that may be related to various aspects of the present disclosure described herein, which are described and/or claimed below. This discussion is believed to be helpful in providing the reader with background information to facilitate a better understanding of the various aspects of the present disclosure described herein. Accordingly, it should be understood that these statements are to be read in this light, and not as admissions of prior art.

Generally, when a person perspires, their perspiration fluids from the person's forehead and flows downward and often flows into the person's eyes. To overcome this problem, there are currently numerous headbands that can absorb the perspiration on the forehead before it can flow into one's eyes. In this respect, throughout the years, a number of innovations have been developed relating to perspiration absorbent headbands. One problem associated with any headband that absorbs perspiration is the problem of saturation. When the headband becomes saturated with perspiration, it can no longer absorb perspiration. As a result, either the wearer must take the headband off and squeeze out the absorbed perspiration, or excess perspiration will flow out from the saturated absorbent.

Hence, what is needed is a headband that prevents sweat and perspiration fluids from getting in one's eyes, is moisture resistance and does not become saturated, is simple to place and adjust to a user's head, incorporates light weight material, hygienic, and can be further customized to a user's liking.

BRIEF SUMMARY

The disclosure described herein overcomes the above-mentioned shortfalls of prior attempted methods and devices. In particular, in one aspect of the disclosure described herein, a method, and apparatus are provided for perspiration diverting headband that can divert perspiration away from a user's forehead (frontal region) to the side or temporal regions and/or off the user's forehead. In addition, the headband of the disclosure described herein is simple to use and adjust, simple to manufacture, made of light weight moisture resistant and anti-microbial material, hygienic, and can be customized and configured to any shape, color, or design.

In another aspect of the disclosure described herein, a perspiration diverting headband is provided having a flexible tubing having a first and second end, an elastic band, wherein the band is disposed within the tubing, a first connector coupled to the first end of the tubing, and a second connector coupled to the second end of the tubing, wherein

2

the first and second connector secure the elastic band and tubing, and a slidable tension fastener configured to secure the elastic band. In addition, the tubing can be a flexible tubing that is cylindrical. Further, the flexible tubing can be configured to divert perspiration fluids away from a forehead region to a temple region of a user's head. The slidable tension fastener can receive the first and second end of the elastic band. Further, the first and second connector further comprise a first and second region, wherein the elastic band is secured in a second region and wherein the band can slide with respect to the second region.

In another aspect of the disclosure described herein, a perspiration diverting headband is provided having a flexible tubing having a first and second end, an elastic band having a first end and second end, wherein the band is disposed within the tubing. In addition, a first connector coupled to the first end of the tubing, and a second connector coupled to the second end of the tubing, wherein the first and second connector secure the elastic band and tubing. Further, a first slidable fastener can be secured to the first end of the elastic band and configured to slide with respect to the second end of the elastic band, and a second slidable fastener can be secured to the second end of the elastic band and configured to slide with respect to the first end of the elastic band. Also, the flexible tubing can be cylindrical in shape. Further, the flexible tubing can be configured to divert perspiration fluids away from a forehead region to a temple region of a user's head. The slidable tension fastener can receive a first and second end of the elastic band. The first and second connector further includes a first and second region, wherein the elastic band is secured in a second region and wherein the band can slide with respect to the second region.

In another aspect of the disclosure described herein, a method for diverting perspiration fluids is provided. The method can include securing a headband around a user's head, wherein a tubular part at least partially covers the user's forehead region, receiving perspiration fluids from the user's forehead region on the tubular part, and diverting the perspiration fluid along tubular part and away from the forehead region. In addition, the perspiration fluid can be received within a crevice between a surface of the tubular part and a surface of the forehead region of the user. Also, the perspiration fluid can be further guided to the temple region of the user.

In another aspect of the disclosure described herein, a perspiration diverting headband is disclosed. The headband can include a flexible tubing having a first end and a second end, and an elastic band a first end and a second end, wherein the elastic band extends through and out the first end and second end of the flexible tubing. In addition, the headband can include a first tubular connector secured to the first end of the tubing and at least partially disposed over the elastic band, wherein the elastic band further extends through and out the first tubular connector, and a second tubular connector secured to the second end of the tubing and at least partially disposed over the elastic band, wherein the elastic band further extends through and out the second tubular connector. Further, the headband can include a first slidable fastener having an opening for receiving the elastic band, wherein the elastic band slides through the opening of the first slidable fastener, and a second slidable fastener having an opening for receiving the elastic band, wherein the elastic band slides through the second slidable fastener. Further, the first slidable fastener can be coupled to the first end of the elastic band, and the second slidable fastener is coupled to the second end of the elastic band. In addition, the flexible

tubing can be configured to divert perspiration way from a forehead region to a side region of a user's head.

The above summary is not intended to describe each and every disclosed embodiment or every implementation of the disclosure. The Description that follows more particularly exemplifies the various illustrative embodiments.

BRIEF DESCRIPTION OF THE DRAWINGS

The following description should be read with reference to the drawings, in which like elements in different drawings are numbered in like fashion. The drawings, which are not necessarily to scale, depict selected embodiments and are not intended to limit the scope of the disclosure. The disclosure may be more completely understood in consideration of the following detailed description of various embodiments in connection with the accompanying drawings, in which:

FIG. 1 illustrates a perspective top view of one non-limiting embodiment for the headband of the disclosure described herein.

FIG. 2 illustrates a cross sectional side view of a connector and band for the headband of the disclosure described herein.

FIG. 3A illustrates a perspective side view of the headband and a user, further illustrating the headband diverting perspiration fluids away from the forehead region of the user.

FIG. 3B illustrates a cross-section side view of the headband and the user's forehead, further illustrating headband diverting perspiration fluids away from the forehead region of the user.

FIG. 4A illustrates a perspective left side view of the headband of the disclosure described herein, as worn by a user.

FIG. 4B illustrates a perspective right side view of the headband of the disclosure described herein, as worn by a user.

FIG. 4C illustrates a perspective rear view of the headband of the disclosure described herein, as worn by a user.

FIG. 4D illustrates a perspective front view of the headband of the disclosure described herein, as worn by a user.

FIG. 5 illustrates a perspective top view of another non-limiting embodiment for the headband of the disclosure described herein.

FIG. 6 illustrates a perspective top view of another non-limiting embodiment for the headband of the disclosure described herein.

FIG. 7A illustrates a cross sectional side view of a connector and band for the headband of the disclosure described herein.

FIG. 7B illustrates a perspective side view of the headband and a user, further illustrating the headband diverting perspiration fluids away from the forehead region of the user.

FIG. 7C illustrates a cross-section side view of the headband and the user's forehead, further illustrating headband diverting perspiration fluids away from the forehead region of the user.

FIG. 8A illustrates a perspective left side view of the headband of the disclosure described herein, as worn by a user.

FIG. 8B illustrates a perspective right side view of the headband of the disclosure described herein, as worn by a user.

FIG. 8C illustrates a perspective rear view of the headband of the disclosure described herein, as worn by a user.

FIG. 8D illustrates a perspective front view of the headband of the disclosure described herein, as worn by a user.

DETAILED DESCRIPTION

In the Brief Summary of the present disclosure above and in the Detailed Description of the Disclosure described herein, and the claims below, and in the accompanying drawings, reference is made to particular features (including method steps) of the disclosure described herein. It is to be understood that the disclosure of the disclosure described herein in this specification includes all possible combinations of such particular features. For example, where a particular feature is disclosed in the context of a particular aspect or embodiment of the disclosure described herein, or a particular claim, that feature can also be used, to the extent possible, in combination with and/or in the context of other particular aspects and embodiments of the disclosure described herein, and in the disclosure described herein generally.

FIGS. 1-4 illustrate various views of the headband of the disclosure described herein according to one non-limiting embodiment. Specifically, headband 100 includes a moisture resistance brow flexible cylindrical tubing 110 connected at its ends to elastic flexible cylindrical rubber fasteners 120a and 120b, wherein fasteners or connectors 120a and 120b further couple and connect tubing 110 to elastic band 130a and 130b. In this embodiment, bands 130a and 130b are one unitary piece, wherein the bands 130a and 130b run through an interior hollow channel of tubing 110 and terminate at terminator end 150. However, in other embodiments, bands 130a and 130b can be two separate pieces, wherein the band does not run through the tube 110, wherein tubing 110 can be a solid non-hollow piece, and connect to tubing 110 at fasteners 120a and 120b. Referring back to the current embodiment, band portions 130a and 130b are further connected to sliding tensioner fastener 140. Here, fastener 140 allows bands 130a and 130b to securely fit around a user's head and secure the headband in place, as shown in FIGS. 3 and 4A-4D. Finally, terminator end 150 allows the ends of bands 130a and 130b to fit securely therein, thereby preventing the ends to hang freely and further preventing fastener 140 for sliding off of bands 130a and 130b. Here, tensioner fastener 140 can be adjusted along band 130a and 130b by depressing a top button thereby releasing and disengaging its tension on bands 130a and 130b and further releasing the button which will again re-engage bands 130a and 130b.

Referring now to FIG. 2, a cross-sectional side view of connector 120a is shown, wherein the connectors 120b will have an identical structure. More specifically, connector 120a has a first region 122a and a second region 124a, wherein region 122a has a larger diameter than region 124a. Here, adhesives 126a are used within region 122a to secure and connect band 130a (and also band 130b) to the connector 120a, thereby also securing tubing 110 (not shown) and preventing tubing 110 from sliding with respect to either of bands 130a and 130b. In contrast, band 130a can slide and expand within region 124a, where it is not fixed, which can allow the band to stretch more and be more expandable and flexible.

Referring now to FIGS. 3A and 3B, tubing 110 can be a moisture resistant flexible and elastics material that provides a barrier against sweat and perspiration on the forehead of a user. For example, if a user 170 is perspiring sweat beads or perspiration fluid 172 around the forehead (frontal) regions, and the user's head is positioned upright or slightly tilted

backwards, then the headband tubing 110 can divert the perspiration fluid 172 from the forehead (frontal region) to and around the side and temporal regions of the head and off of the user's head, as shown in FIGS. 3A and 3B. Alternatively, if the user's head is slightly tilted forward, then the perspiration fluid can flow over the tubing 110 and off the head, preventing the perspiration fluid from falling in the user's eyes. FIG. 3B illustrates a partial cross-section of the tubing 110, having bands 130a/130b therein, wherein the cylindrical tubing can create a crevice between the surface of the user's forehead and surface of the tubing, and wherein the perspiration fluid 172 can be guided along the crevice and subsequently off of the tubing.

FIG. 5 illustrates another embodiment for the perspiration diverting brow headband of the disclosure described herein. Specifically, headband 200 includes a moisture resistance tubing 210 connected at its ends to elastic rubber fasteners 220a and 220b, wherein fasteners or connectors 220a and 220b further couple and connect tubing 210 to elastic band 230a and 230b. In this embodiment, bands 230a and 230b are one unitary piece, wherein the bands 230a and 230b run through an interior hollow channel of tubing 210 and terminate at terminator ends 250a and 250b. However, in other embodiments, bands 230a and 230b can be two separate pieces, wherein the band does not run through the tube 210, wherein tubing 210 can be a solid non-hollow piece, and connect to tubing 210 at fasteners 220a and 220b. Referring back to the current embodiment, bands portions 230a and 230b are further connected and looped through an opening of sliding fasteners 240a and 240b, respectively. Terminator ends 250a and 250b allow the ends of bands 230a and 230b, that have been looped through fastener's 240a and 240b, to be secured and tightened in place, thereby preventing the ends of bands 230a and 230b to hang freely and further preventing fasteners 240a and 240b for sliding off of bands 230a and 230b.

Still referring to FIG. 5, fastener 240a and 240b can be slid and adjusted with respect to bands 230a and 230b to securely fit around a user's head and secure the headband in place. More specifically, fastener 240a can receive band 230b through an opening and slide with respect to band 230b, and fastener 240b can receive band 230a and slide with respect to band 230a. The sliding of either of fasteners 240a and 240b, or both, can allow the user to configure the correct size of the band for placement on his or her head. Once the headband 200 is placed around the user's head, the tension in the bands and the rubber fasteners 240a and 240b, including friction, prevent slippage or sliding of the fasteners along either of bands 230a and 230b.

FIG. 6 illustrates another embodiment for the perspiration diverting brow headband of the disclosure described herein. Specifically, headband 300 includes a moisture resistance tubing 310 connected at its ends to elastic rubber fasteners 320a and 320b, wherein fasteners or connectors 320a and 320b further couple and connect tubing 310 to elastic band 330a and 330b. In this embodiment, bands 330a and 330b are one unitary piece, wherein bands 330a and 330b run through an interior hollow channel of tubing 310 and terminate at terminator ends 350a and 350b. However, in other embodiments, bands 330a and 330b can be two separate pieces, wherein the band does not run through the tube 310, wherein tubing 310 can be a solid non-hollow piece, and connect to tubing 310 at fasteners 320a and 320b. Referring back to the current embodiment, bands portions 330a and 330b are further connected and looped through an opening of sliding fasteners 340a and 340b, respectively. In this embodiment, fasteners 340a and 340b can have circular

looped openings and also be made of a ridged or flexible material that is further fused to ends 250a and 250b, respectively. Fasteners 340a and 340b can allow for easy adjustment of the size of band 300, wherein fasteners 340a and 340b grip the exterior surface of each band portion 330a and 330b, respectively, once band 300 is stretched and placed around the user's head. Here, terminator ends 350a and 350b can allow the ends of bands 330a and 330b, that have been looped through fastener's 340a and 340b, to be secured and tightened in place, thereby preventing the ends of bands 330a and 330b to hang freely and further preventing fasteners 340a and 340b for sliding off of bands 330a and 330b.

Still referring to FIG. 6, fasteners 340a and 340b can be slid and adjusted with respect to bands 330a and 330b to securely fit around a user's head and secure the headband in place. More specifically, fastener 340a can receive band 330b through an opening and slide with respect to band 330b, and fastener 340b can receive band 330a and slide with respect to band 330a. The sliding of either of fasteners 340a and 340b, or both, can allow the user to configure the correct size of the band for placement on his or her head. Once the headband 300 is placed around the user's head, the tension in the bands and the rubber fasteners 340a and 340b, including friction, prevent slippage or sliding of the fasteners along either of bands 330a and 330b.

Referring now to FIG. 7A, a cross-sectional side view of connector 320a is shown, wherein the connectors 320b will have an identical structure. More specifically, connector 320a has a first region 322a and a second region 324a, wherein region 322a has a larger diameter than region 324a. Here, adhesives 326a are used within region 322a to secure and connect band 330a (and also band 330b) to the connector 320a, thereby also securing tubing 310 (not shown) and preventing tubing 310 from sliding with respect to either of bands 330a and 330b. In contrast, band 330a can slide and expand within region 324a, where it is not fixed, which can allow the band to stretch more and be more expandable and flexible. A first tubular connector having a proximal region with a first diameter and a distal region with a second diameter, wherein the second diameter of the distal region is smaller relative to the first diameter of the proximal region of the first tubular connector, wherein the proximal region with the first diameter of the first tubular connector is secured to the first end of the tubing and disposed over the elastic band, wherein the elastic band further extends through and out the first tubular connector. A second tubular connector having a proximal region with a third diameter and a distal region with a fourth diameter, wherein the fourth diameter of the distal region is smaller relative to the third diameter of the proximal region of the second tubular member, wherein the proximal region with the third diameter of the second tubular connector is secured to the second end of the tubing and disposed over the elastic band, wherein the elastic band further extends through and out the second tubular connector.

Referring now to FIGS. 7B and 7C, tubing 310 can be a moisture resistant flexible and elastics material that provides a barrier against sweat and perspiration on the forehead of a user. For example, if a user 370 is perspiring sweat beads or perspiration fluid 372 around the forehead (frontal) regions, and the user's head is positioned upright or slightly tilted backwards, then the headband tubing 310 can divert the perspiration fluid 372 from the forehead (frontal region) to and around the side and temporal regions of the head and off of the user's head, as shown in FIGS. 7B and 7C. Alternatively, if the user's head is slightly tilted forward, then the

perspiration fluid can flow over the tubing 310 and off the head, preventing the perspiration fluid from falling in the user's eyes. FIG. 7C illustrates a partial cross-section of the tubing 310, having bands 330a/330b therein, wherein the cylindrical tubing can create a crevice between the surface of the user's forehead and surface of the tubing, and wherein the perspiration fluid 372 can be guided along the crevice and subsequently off of the tubing.

It is contemplated within the scope of the disclosure described herein that bands 130a, 130b, 230a, 230b, 330a, and 330b can be stretchable, flexible, and elastic. However, it is contemplated within the scope of the disclosure described herein that bands 130a-330b can also be of a non-elastic type and be made of any suitable material. Further, fasteners 140, 240a, 240b, 340a, and 340b can be any type of fastener that allows the bands 130a-330b to securely fit around the user's head. For example, fasteners 140, 240a, 240b, 340a, and 340b can also be a biased or spring biased based tensioner having a button. Here, when the button is depressed the tension is released on the band and the fastener can slide along the band, and when the button is released the fastener can be locked or secured in place. In addition, fasteners 140, 240a, 240b, 340a, and 340b can be any type of strap, buckle, cam, clasp, button, or hook and loop material (Velcro®). In addition, fasteners 140, 240a, 240b, 340a, and 340b can include but is not limited to cotton based materials, polymer based materials, elastic material, rubber material, polymer based, metal cam straps, plastic cam buckle straps, camera straps, D-ring, double D-ring straps, flat hook straps, wire hook straps, loop straps, ratchet straps, side release buckle straps, simple sling straps, strap adjuster straps, D-ring belts, side release buckle belts, double three bar slide belts, and/or double o-ring belts.

Here, tubing 110, 210, 310, bands 130a, 130b, 230a, 230b, 330a, and 330b can be hollow or solid and have a cross-section that is cylindrical, circular, rectangular, or square, or any polygon having three or more sides. Further, tubing 110, 210, 310, bands 130a, 130b, 230a, 230b, 330a, and 330b can be made of materials including but not limited to: moisture and liquid resistant materials, low moisture absorbing materials, heat activated materials, moisture and liquid activated materials, anti-microbial and/or anti-bacterial materials, waterproof materials, moisture resistant fabric/mesh/rubber, polyester based materials, cotton based materials, rubber based materials, neoprene rubber, foam based, plastic based materials, poly based materials, padding, gel based, polymer based, elastic material, viscoelastic material, Gore-Tex®, silicone rubber rolls, commercial silicone, high temperature silicone, cloth silicone, FDA silicone, transparent silicone, translucent silicone, silicone ZZR-765 Rubber, NSF 51 compliant silicone, neoprene rubber, EPDM rubber, Nitrile (Buna-N) rubber, natural gum rubber, Viton® rubber, hypalon rubber, SBR rubber, butyl rubber, latex rubber, santoprene rubber, skirtboard rubber, elastomer, rubber, natural rubber, fillers, additive fillers, epoxy derived, synthetic rubber, polymer, polyurethane, polycarbonate, or any one or more combination of the aforementioned materials. In addition, tubing 110 and band 130 can be of any color code and have any type of indicia, such as text, graphics, images, and artwork.

It is contemplated within the scope of the disclosure described herein that the headband can be used in any type of industry and for any type of application, including but not limited to athletics, sports, recreational, retail, medical, home, or commercial uses. In addition, any of the of the headband or aforementioned parts and components, including but not limited to the tubing, band, and fasteners can be

customized and personalized and be configured to be of any shape/design/dimension having any color/artwork or indicia and can be transparent, semi-transparent, or opaque.

Having thus described the several embodiments of the disclosure described herein, those of skill in the art will readily appreciate that other embodiments may be made and used which fall within the scope of the claims attached hereto. Numerous advantages of the disclosure described herein covered by this document have been set forth in the foregoing description. It will be understood that this disclosure is, in many respects, only illustrative. Changes can be made with respect to various elements described herein without exceeding the scope of the disclosure described herein. Although the present disclosure described herein has been described in considerable detail with reference to certain preferred versions or embodiments thereof, other versions and embodiments are possible.

The invention claimed is:

1. A perspiration diverting headband, the headband comprising:

a flexible tubing having a first end and a second end; an elastic band having a first end and a second end, wherein the elastic band extends through and out the first end and second end of the flexible tubing;

a first tubular connector having a first cross-section region and a second cross-section region directly adjacent to each other, wherein the second cross-section region of the first tubular connector is smaller in diameter or height relative to the first cross-section region of the first tubular connector, wherein the first tubular connector is secured to the first end of the tubing and disposed over the elastic band via the first cross-section region of the first tubular connector, wherein the elastic band further extends through and out the first tubular connector;

a second tubular connector having a first cross-section region and a second cross-section region directly adjacent to each other, wherein the second cross-section of the second tubular connector is smaller in diameter or height relative to the first cross-section of the second tubular connector, wherein the second tubular connector is secured to the second end of the tubing and disposed over the elastic band via the first cross-section region of the second tubular connector, wherein the elastic band further extends through and out the second tubular connector;

a first slidable fastener having an opening receiving the elastic band, wherein the elastic band slides through the opening of the first slidable fastener; and

a second slidable fastener having an opening receiving the elastic band, wherein the elastic band slides through the opening of the second slidable fastener.

2. The perspiration diverting headband of claim 1, wherein the first slidable fastener is coupled to the first end of the elastic band, and the second slidable fastener is coupled to the second end of the elastic band.

3. The perspiration diverting headband of claim 1, wherein the flexible tubing is configured to divert perspiration way from a forehead region to a side region of a user's head.

4. A perspiration diverting headband, the headband comprising:

a flexible tubing having a first end and a second end; an elastic band having a first end and a second end; a first tubular connector having a proximal region with a first diameter and a distal region with a second diameter, wherein the second diameter of the distal region is

smaller relative to the first diameter of the proximal region of the first tubular connector, wherein the proximal region with the first diameter of the first tubular connector is secured to the first end of the tubing and disposed over the elastic band, wherein the elastic band further extends through and out the first tubular connector; 5

a second tubular connector having a proximal region with a third diameter and a distal region with a fourth diameter, wherein the fourth diameter of the distal region is smaller relative to the third diameter of the proximal region of the second tubular member, wherein the proximal region with the third diameter of the second tubular connector is secured to the second end of the tubing and disposed over the elastic band, 10 wherein the elastic band further extends through and out the second tubular connector;

a first slideable fastener having an opening receiving the elastic band, wherein the elastic band slides through the opening of the first slideable fastener; and 20

a second slideable fastener having an opening receiving the elastic band, wherein the elastic band slides through the opening of the second slideable fastener.
